UNITED STATES PATENT OFFICE

SOLOMON N. REVIS, OF ASHLAND, NEBRASKA, ASSIGNOR TO VERNON ELMER REVIS, OF ASHLAND, NEBRASKA

CORN SHELLER

Application filed June 1, 1931. Serial No. 541,433.

The invention relates to a sheller and more especially to a corn sheller.

The primary object of the invention is the provision of a machine of this character wherein the same is constructed to take care of an overflow and also to compensate for the feed of the material to the shelling rolls without liability of choking or the breaking of the cob during the feeding operation.

10 Another object of the invention is the provision of a machine of this character wherein the concaves for the shelling rolls are mounted in a novel manner to exert the proper pressure upon the material when acted upon by 15 the shelling rolls and also to avoid choking or the breaking of the corn cob during shell- ing operation.

A further object of the invention is the provision of a machine of this character 20 wherein the construction thereof is novel in form to assure a perfect shelling operation and to avoid undue overflow as the capacity of the machine is augmented by a supplemental overflow roller to take care of excess 25 feeding material thereto.

A still further object of the invention is the provision of a machine of this character which is simple in construction, thoroughly reliable and efficient in operation, strong, 30 durable, and inexpensive to manufacture.

With these and other objects in view, the invention consists in the features of construction, combination and arrangement of parts 35 as will be hereinafter more fully described in detail, illustrated in the accompanying drawings, which disclose the preferred embodiment of the invention, and pointed out in the claim hereunto appended.

40 In the accompanying drawings:—

Figure 1 is an elevation of a corn sheller constructed in accordance with the invention.

Figure 2 is a vertical longitudinal sectional view thereof.

45 Figure 3 is a top plan view with portions thereof broken away.

Figure 4 is a sectional view on the line 4—4 of Figure 2 looking in the direction of the arrows.

50 Similar reference characters indicate cor-

responding parts throughout the several views in the drawings.

Referring to the drawings in detail, the machine comprises a box-like body 5 open at its top and bottom and is preferably of 55 rectangular contour having journaled trans- versely therein a pair of corn shelling rolls 6 and an overflow corn shelling roll 7, the journals 8 of these rolls being suitably mounted in the longitudinal sides of said body 5 60 and at one side of the latter these journals are extended to carry belt wheels 9, these being made fast to said journals in any suit- able manner and have trained thereover an endless belt 10, the upper stretch 11 of which 65 is alternately trained over said wheels 9 so that the said upper stretch will be disposed at the lowermost side of the intermediate wheel and at the highest side of the outer 70 wheel 9 of the series so that in this manner the pair of rolls 6 will be driven in reverse directions to each other while the wheel 9 to the supplemental roll 7 will be driven in the same direction as the intermediate wheel of those connected to the pairs of rolls 6 and 75 supplemental roll 7.

Above the rolls 6 and 7 and fixed to the side wheels of the body 5 are feed baffles or deflector plates 12 and 13 respectively, the latter being for the supplemental roll 7, while 80 the plate 12 is for the pair of rolls 6. It is of course understood that the rolls 6 and 7 are toothed as at 14 in the usual manner.

Arranged below the outermost roll 6 of the pair and also the remaining roll of said pair 85 and the supplemental roll 7 are wire concaves 15 and 16, the latter being of dual formation while the concave 15 is of the single type. The concave 15 has one end edge secured at 17 to the end of the body 5 90 while the other end edge is curled at 18 about a cross support 19, the latter slidably fitted in vertical slots 30 in the sides of the body 5 and this curled end 18 having the support 19 therein is yieldably held by coiled springs 21 suitably mounted within the slots 20 and thus in this manner the concave 15 is yield- ably supported to compensate for crowding of corn cobs passing beneath the roll 6 of the pair confronted by said concave 15. The 100

- concave 16 of the dual type is stationarily supported between the other roll 6 of the pair and the supplemental or overflow roll 7 by a stationary cross supporting bar 22 while the 5 outer ends of said concave 16 are curled at 23 about slidable supports 24 in vertical slots 25 in the side of the body 5, these curled ends 23 and their supports 24 being acted upon by coiled tensioning springs 26 mounted 10 within the slots 25 so that the said concave 16 in its dual formation will compensate for crowding beneath the roll 6 of said pair and the supplemental roll 7 to avoid choking of the machine and also to eliminate the 15 breaking of the corn cobs during the shelling operation, yet the required pressure upon the material will be had for the proper shelling of the cobs by the rolls 6 and 7 in the working of said machine.
- 20 One of the journals for the rolls 6 carries a power pulley 27 whereby the machine may be operated.

In the operation of the machine under a normal load or feed the pair of shelling 25 rolls 6 will take care of the same but should an overload or an overflow be had in the feeding of the machine with corn ears then this overflow will be taken care of by the supplemental roll 7 and such overflow shelled 30 in the working of the machine.

What is claimed is:—

In a corn sheller, a body open at its top and bottom, a plurality of rolls journaled transversely in the body in spaced relation to 35 each other in a horizontal row, foraminous concaves disposed below the rolls, one of the concaves being fixed intermediate thereof between two of said rolls with its ends yieldably supported, the other concave having one 40 fixed end and a yieldably supported other end, feeder plates above the rolls forming a hopper and disposed for directing materials toward the fixed points of the concaves, and connections between the rolls for operating 45 the same in unison.

In testimony whereof I affix my signature.
SOLOMON N. REVIS.
